UNITED STATES PATENT OFFICE.

DAVID NUSBAUM, OF NEW YORK, N. Y., ASSIGNOR TO D. NUSBAUM & CO., INC., OF UNION COURSE, LONG ISLAND, NEW YORK, A CORPORATION OF NEW YORK.

DESIGN FOR A SWEATER.

60,804.

Specification for Design. Patented Apr. 11, 1922.

Application filed November 26, 1921. Serial No. 518,097. Term of patent 7 years.

To all whom it may concern:

Be it known that I, DAVID NUSBAUM, a citizen of the United States of America, and a resident of the borough of Queens, city and State of New York, have invented a new, original, and ornamental Design for Sweaters, of which the following description, in connection with the accompanying drawing, is a specification.

Figures 1 and 2 are front and rear views respectively of said sweater, and Figure 3 a detailed view of the fabric of said sweater, showing my new design.

I claim as my invention:

The ornamental design for a sweater, as shown.

DAVID NUSBAUM.
